WOMAN'S SCARF

Erwin B. Jackman, Brooklyn, N. Y.

Application December 24, 1953, Serial No. 28,213

Term of patent 14 years

(Cl. D3—16)

To all whom it may concern:

Be it known that I, Erwin B. Jackman, a citizen of the United States of America and a resident of Brooklyn, New York, have invented a new, original, and ornamental Design for a Woman's Scarf, of which the following is a specification, reference being had to the accompanying drawing, forming a part hereof.

The figure is a plan view of a woman's scarf showing my new design.

I claim:

The ornamental design for a woman's scarf, substantially as shown.
